CLAIM

The ornamental design for a mobile terminal, as shown and described.

DESCRIPTION

FIG. 1 is a front perspective view of a mobile terminal;
FIG. 2 is a front view of the mobile terminal of FIG. 1;
FIG. 3 is a rear view of the mobile terminal of FIG. 1;
FIG. 4 is a left-side view of the mobile terminal of FIG. 1;
FIG. 5 is a right-side view of the mobile terminal of FIG. 1;
FIG. 6 is a top plan view of the mobile terminal of FIG. 1;
FIG. 7 is a bottom plan view of the mobile terminal of FIG. 1;
and,

FIG. 8 is an open front view of the mobile terminal of FIG. 1.
Features shown in broken lines in FIGS. 1, 2, 4, 5, 6, 7, and 8
form no part of the claimed design. The keypad region at the
lower portion of the front in FIGS. 1, 2, and 8 and the interior
surface in FIG. 8, both of which encompass broken line
showings and are defined by solid line boundaries, form no
part of the claimed design.
